(57) CLAIM

The ornamental design for a pedicure spa, as shown and described.

DESCRIPTION

FIG. 1 is a perspective view showing the front, left and top of a pedicure spa showing my new design; the broken lines shown in the drawings represent unclaimed portions of the design and forms no part thereof.

FIG. 2 is a top view of the pedicure spa, such as that shown in FIG. 1;

FIG. 3 is a right side view of the pedicure spa, such as that shown in FIG. 1, the left side view being similar to that shown in FIG. 3;

FIG. 4 is a front view of the pedicure spa, such as that shown in FIG. 1; and,

FIG. 5 is a rear view of the pedicure spa, such as that shown in FIG. 1.
